UNITED STATES PATENT OFFICE.

HARRY E. HOWARD, OF CHICAGO, ILLINOIS.

EXTENSION-LADDER.

SPECIFICATION forming part of Letters Patent No. 650,604, dated May 29, 1900.

Application filed August 15, 1898. Renewed November 14, 1899. Serial No. 736,999. (No model.)

To all whom it may concern:

Be it known that I, HARRY E. HOWARD, a citizen of the United States, residing at Chicago, in the county of Cook and State of Illinois, have invented certain new and useful Improvements in Extension-Ladders, of which the following is a specification.

My invention relates to improvements in extension-ladders; and the object of my improvements is to provide a portable ladder of this character in which the coupling of the sections may be obtained with the maximum degree of strength, in which antifrictional means are employed, whereby the sliding of one section over the other is quickly and easily accomplished, and in which the coupling and antifrictional device will not interfere with the ordinary use of the ladder with safety to the user.

10 I am aware that sectional ladders have been provided with appliances for reducing the friction resulting in sliding one section over the other and that various forms of couplings have been employed to secure the sections together. One appliance consists of a bracket or yoke extending outwardly from the ladder and in which is mounted a roller which extends transversely across the ladder, the sliding section bearing against the roller. The 15 objection to this device is that the bracket projects so much from the outer face or plane of the ladder that it compels the user to swing his body and limbs so far out as to endanger his hold, or it is likely to cause him to catch his foot in the bracket, and thus produce a fall. Another device consists of two brackets secured to the side rails of one section of the ladder, in each of which is mounted a frictional roller. The defects in this appliance 20 are that the brackets twist or yield laterally, thus causing the rollers to run unevenly and eventually permitting displacement of the upper section. This construction embodies no bracing features, there being no connection between the individual brackets.

Having become cognizant of the defects above set forth from my experience as a manufacturer of extension-ladders, it has been the aim of my invention to overcome them in a simple and economical manner, which will be set

forth in detail and which is illustrated in the accompanying drawings, which form a part of my application for patent, and in which—

Figure 1 shows in perspective view the application of my invention to two sections of 55 an extensible ladder. Fig. 2 is a detail perspective view of my invention, and Fig. 3 is a transverse section on line xx of Fig. 1.

My invention consists of a combined bracket and yoke A, which is formed from a 60 single piece of flat or strap metal. Its opposite ends are bent up to form flanges a , which are perforated for the reception of bolts, by means of which the bracket is bolted to the rear or under side of the side rails b of the 65 first or ground section of the ladder. The yoke-strap is again bent at the points $c c$, whereupon it takes a U-shaped form, the sides of which are indicated by the letters $d d$. These sides are perforated near the flanges a 70 for the reception of bolts, which are caused to pass through the side rails b of the ground-section of the ladder at right angles to the flange-bolts above mentioned. The yoke-strap is then bent inwardly at $e e$, forming 75 short arms f , which are parallel with the sides d .

Mounted in suitable openings in the parts d and f are the spindles, on which are fixed the rollers $g g$, the latter being slightly longer 80 than the cross-diameter of the side rails h of the upper or extensible section of the ladder, against which they bear when the various parts are in operative positions, as shown in Fig. 1.

It will be noted that the central portion i of the yoke lies within the outer face or plane of the side rails h and, in fact, is almost to the rungs of said upper section, thus being entirely out of the way of the feet of the user, 90 at the same time forming a connecting and bracing band between the roller-bearing portions on either side of the yoke, which imparts strength and rigidity to the device, while it also serves effectually to prevent displacement of the upper section of the ladder.

Additional strength and rigidity are obtained by the double bends c and e , as will be readily apparent. It will also be apparent that the central part i may be divided vertically 95

100

and one half slotted and the other half provided with a bolt and nut, and by bolting the two sections together the yoke may be adjusted to ladders of different widths. This and other minor modifications may be made within the scope of my invention.

Having thus described my invention, what I claim as new, and desire to secure by Letters Patent, is—

10. 1. In combination with stationary and extensible sections of a ladder, a bracket or yoke bent in **U** shape near each end to form bearings for rollers, and having a bar connecting said **U**-shaped portion, said bar lying within the plane of the extensible section, and roll-

ers mounted in said **U**-shaped portions, substantially as set forth.

2. A bracket or yoke composed of a single piece of metal outwardly bent in **U** shape near each end to form bearings for rollers, and having its central portion connecting said **U**-shaped portions lying within the plane of the latter, and rollers mounted in said **U**-shaped portions, substantially as set forth.

In testimony whereof I affix my signature in presence of two witnesses.

HARRY E. HOWARD.
